UNITED STATES PATENT OFFICE.

ENOCH HOIBY, OF MINNEAPOLIS, MINNESOTA.

DESIGN FOR A TRUCK-BODY.

44,923.

Specification for Design.

Patented Nov. 25, 1913.

Application filed October 3, 1912. Serial No. 723,778. Term of patent 14 years.

To all whom it may concern:

Be it known that I, ENOCH HOIBY, a citizen of the United States, residing at Minneapolis, in the county of Hennepin and State of Minnesota, have invented a new, original, and ornamental Design for a Truck-Body, of which the following is a specification, reference being had to the accompanying drawing, forming part thereof.

The figure is a perspective view of a truck body showing my design.

I claim:

The ornamental design for a truck body, as shown.

ENOCH HOIBY.

In the presence of—

F. D. MERCHANT,
HARRY D. KILGORE.
